US00D910227S

(12) **United States Design Patent** (10) Patent No.: **US D910,227 S**
(45) Date of Patent: ** Feb. 9, 2021

(54) **PROJECTOR**

(71) Applicant: **J.W. SPEAKER CORPORATION**,
Germantown, WI (US)

(72) Inventors: **Eric J. Deering**, Hartland, WI (US);
Bradley W. Kay, Mequon, WI (US)

(73) Assignee: **J.W. SPEAKER CORPORATION**,
Germantown, WI (US)

(**) Term: **15 Years**

(21) Appl. No.: **29/668,412**

(22) Filed: **Oct. 30, 2018**

(51) LOC (13) Cl. **26-05**

(57) **CLAIM**

The ornamental design for a projector, as shown and described.

DESCRIPTION

FIG. 1 is an isometric view of a front, top, and right side of an ornamental design for a projector;

FIG. 2 is a front elevational view of the projector of FIG. 1; FIG. 3 is a rear elevational view of the projector of FIG. 1; FIG. 4 is a right side elevational view of the projector of FIG. 1;

FIG. 5 is a left side elevational view of the projector of FIG. 1;

FIG. 6 is a top plan view of the projector of FIG. 1; FIG. 7 is a bottom plan view of the projector of FIG. 1; and, FIG. 8 is an isometric view of the rear, top, and left side of the projector of FIG. 1.

The dash-dash-dash lines are for the purpose of illustrating environmental structure and form no part of the claimed design. The dash-dot-dash lines form no part of the claimed design and represent a boundary line.

1 Claim, 6 Drawing Sheets
